UNITED STATES PATENT OFFICE.

ROBERT G. CLYNE, OF ALTON, ILLINOIS.

MUSHROOM-BULLET.

1,135,357.

Specification of Letters Patent. Patented Apr. 13, 1915.

Application filed February 11, 1914. Serial No. 817,973.

To all whom it may concern:

Be it known that I, ROBERT G. CLYNE, a subject of the King of Great Britain, residing at Alton, in the county of Madison and State of Illinois, have invented certain new and useful Improvements in Mushroom-Bullets, of which the following is a specification.

My invention relates to improvements in mushroom bullets, the present embodiment relating more particularly to that class or type known as "sharp-nosed" mushroom bullets.

The primary object of the invention is to provide a generally improved mushroom bullet of exceedingly simple, cheap, and efficient construction having superior mushroom qualities.

A still further object is to provide an improved nose or tip adapted not only to be securely engaged or interlocked with the jacket or casing but provided with an improved locking anchor having an enlarged pointed spheroidal shaped spreader head concentrically arranged within and adapted to spread the core portion by the impact of the bullet when striking an object causing sufficient resistance thereby causing the core portion thereof to mushroom or to spread in a superior manner.

A still further object is to provide an improved jacket or casing adapted not only to coöperate and engage with the hard nose or tip of the bullet upon impact but having a weakened or reduced section surrounding the core and anchor or core spreader portion of the bullet thereby facilitating the spreading or mushrooming of the bullet upon impact.

A still further object is to provide a nose or tip for a bullet of this class having an improved anchor adapted not only to be securely engaged and anchored within the core portion thereof but to prevent displacement and maintain the parts in proper relative position when fired thereby keeping the bullet from swerving or going wild in its course.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part

of this specification Figure 1, is a side elevation of a mushroom bullet constructed in accordance with my invention. Fig. 2, a similar view, the anchored nose or tip portion 60 being shown in central longitudinal section. Fig. 3, a side elevation, partly in section, of the metallic jacket or casing, detached. Fig. 4, a similar view of the soft metal slug before being swaged up to form the core. 65 Fig. 5, an end view of the top or open end of the metallic casing or jacket.

Similar numerals of reference designate like parts throughout all the figures of the drawings.

The improved mushroom bullet, comprises a soft metal core 1, preferably of lead or other suitable soft material, and a metallic jacket or casing 2, preferably of nickle or copper. The solid conical nose or tip 3, 75 may be made of the same material, or other suitable hard metal. The conical nose or tip 3, is preferably provided with an annular inset portion 3^a, about its base, said base terminating in a reduced neck portion having an enlarged pointed spheroidal shaped spreader head 3^b, embedded within said core 1.

The open end of the jacket or casing 2, projects beyond and overhangs the said core 1, with its edges 2^a, seated in and interlocking with said annular inset portion 3^a, of the nose or tip 3. As a means of facilitating the telescoping or mushrooming of the parts by impact, the edges 2^a, are preferably beveled or outwardly flaring, as likewise the shoulder portion of the annular inset portion 3^a. The shouldered base portion 3^c, of the nose or tip 3, and the adjacent edges 1^b, of the soft metal core, when assembled, are likewise similarly shaped or beveled for the same purpose. As a means of further facilitating the mushrooming or spreading of the bullet upon impact, the metallic jacket or casing 2, is preferably provided with a 100 weakened or reduced section surrounding that portion of the core which surrounds the pointed spheroidal shaped spreader head 3^b, of the anchor as shown most clearly in Fig. 2 of the drawings. The section 2^b, may be weakened or reduced in any suitable and convenient manner, as for example,—by means of longitudinally extending grooves 2^c, formed in the present instance, on the inner periphery of the casing or jacket 2, 110 as shown most clearly in Figs. 3 and 5 of the drawings.

When the bullet is assembled the slug shown in Fig. 4, is first pushed into the jacket or casing 2, and the pointed spheroidal spreader head 3^b, inserted in the hole 5 in the front end of the slug, just the right quantity of lead or metal being put into the slug so that when the point and anchor are pushed into place the lead or other metal is pushed entirely around the anchor, thereby 10 making a solid bullet and at the same time preventing the point from separating from the body portion.

From the foregoing description, taken in connection with the accompanying drawings, the operation and advantages of my invention will be readily understood.

Having thus described one of the embodiments of my invention, what I claim and desire to secure by Letters Patent is,—

- 20 1. A mushroom bullet, comprising a soft metal core, a solid tip having a pointed spheroidal spreader member embedded within said core, and a jacket normally interlocking with said tip and having interior grooves forming a weakened section surrounding said core and spreader member.
- 25 2. A mushroom bullet, comprising a soft metal core, a jacket having a weakened open end extending over and beyond the forward end of said core, and a solid tip normally interlocking with the open end of said jacket and having a pointed spheroidal spreader head extending in and surrounded by the forward end of said core and jacket.
- 30

Copies of this patent may be obtained for five cents each, by addressing the "Commissioner of Patents, Washington, D. C."

3. A mushroom bullet having a soft metal 35 core, a jacket having a weakened open ended forward section, and a solid tip normally engaging and interlocking with said open ended forward section and provided with an enlarged spheroidal shaped anchor spreader 40 head surrounded by said core and said weakened section.

4. In a mushroom bullet, the combination with a soft metal core, and a conical tip having a reduced neck terminating in a pointed 45 spheroidal spreader head embedded in said core; of a jacket having a longitudinally weakened section surrounding said core about said spreader head and terminating in beveled edges normally interlocking with 50 the base portion of said conical tip.

5. A mushroom bullet, comprising a soft metal core, a conical tip having an annular inset groove about its base, said base terminating in a reduced neck portion having a pointed spheroidal spreader head interlocking with said core, and a jacket having a weakened open ended section surrounding said core about said spreader head and having its open end beveled and interlocking 55 with said annular inset groove of said conical tip.

In testimony whereof I have affixed my signature in presence of two witnesses.

ROBERT G. CLYNE.
